UNITED STATES PATENT OFFICE.

WILLIAM JOHN KNOX, OF NEW YORK, N. Y., ASSIGNOR, BY MESNE ASSIGNMENTS, TO
SAID KNOX AND ARTHUR ROBINS SPEER, OF BRONXVILLE, NEW YORK.

PROCESS AND APPARATUS FOR EXTRACTING HYDROCARBONS FROM OIL WELLS AND OIL-BEARING STRATA.

Application filed April 10, 1919. Serial No. 288,926.

To all whom it may concern:

Be it known that I, WILLIAM JOHN KNOX, a citizen of the United States, residing at New York city, in the county and State of New York, have invented certain new and useful Improvements in Processes and Apparatus for Extracting Hydrocarbons from Oil Wells and Oil-Bearing Strata, of which the following is a specification.

10 My invention relates broadly and generally to new and useful improvements in processes and apparatus whereby the oil and other hydrocarbons existing in subterranean strata and sands can be more fully and 15 economically recovered than by other existing methods, and whereby the rate of flow of the oil and other hydrocarbons can be greatly augmented, and furthermore, whereby that portion of the oil which is ordinarily non-recoverable, is by the use of my 20 invention rendered available and is thereby recovered.

In order to convey a clear understanding of the subject, I will describe the initial 25 conditions existing before a well is drilled and the changes in these conditions which occur during the life of the well. The oil is contained in solid rock strata or densely compacted sand, and would not flow freely 30 unless subjected to the expelling force of gas or other pressure. In some cases the oil is subjected to a hydrostatic pressure, but in all cases the main pressure is caused by 35 condensed vapors and absorbed gases. At the beginning this pressure may be several 40 hundreds of pounds and this locked-in pressure in the dense sand indicates a condensation to the liquid state of all the lighter hydrocarbon vapors and a very high percentage of absorption of the hydrocarbon 45 gases in the oil, in accordance with the well known laws of physics. The pressure is not so much on the oil as, in reality, within the oil.

When the hole is drilled through the rock 50 capping and into the oil-sand, the oil begins to liberate the gases with which it is charged and the liquefied volatile hydrocarbons begin to volatilize with great force and the oil is driven forward by the movement of the gas, the expelling action beginning near the hole and gradually extending further away into the rock. As the light vapors 55 and oils escape, the oil becomes thicker and more viscous and is forced through the fine 60 interstices of the rock with greater difficulty. Eventually the oil becomes so viscous, the gas pressure so weak and the capillary resistance so great that the well ceases almost entirely to yield oil, as the force of 65 gravity is not sufficient to cause it to flow in its thickened condition. It is due to this altered condition of the oil in the sand that oil-well engineers and geologists have reason to believe that much less than fifty per 70 cent of the oil actually in the strata is ever recovered. It is the intent of my process, not only to augment the usual flow of the oil, but to recover the larger portion of this residue oil, and to extend the area of strata 75 from which oil is recoverable to a greater distance from the well.

One of the important objects of my invention is to greatly increase the flow of oil over long periods of time and from 80 greater distances from the well, and is intended to be used continuously or at frequent intervals, preferably not as a separate operation from the oil-pumping, but co-incident therewith, and in integral combination. I have described above the viscous and sluggish condition of the oil in the strata after the excessive vapor and gas 85 pressure have been diminished. It is a well known fact that a small rise in temperature will greatly decrease the viscosity of an oil and render it extremely fluid; paraffin wax, itself, which is one of the residues left in the rock, and is known to cause a retardation of flow, melts at 125° F. or 90 thereabouts. Now the temperature at the bottom of an oil well in the strata is not as a rule over 60° to 70° and this is not sufficient to render the heavy paraffin compounds fluid, but an increase in temperature 95 by my process to 125° or to 150° in the strata causes the oil to flow readily, no matter how thickened it has become. By my method the rock or sand at the bottom of the well, and for extended distances around 100 it, will be heated to the above temperatures in an economical manner, and the oil caused to flow freely and abundantly, even in the case of wells that have practically ceased to produce oil, and in addition, large 105 amounts of gases and vapors are produced.

In carrying out my invention, I conduct heat to the oil-bearing strata at the bottom

of the well by pumping the fluid contents of the well by means of the oil-well pump up to and through a heating device preferably external to the well, then I return this heated or heat-carrying fluid, which is ordinarily crude oil from the well, back into the well by conducting it preferably by suitable pipe connections to the oil-well casing head, whence it falls by gravity again to the bottom of the well. This operation may be a continuous one, the oil-well pump, the heat generating device and the oil well being cyclically connected. To the extent that the heat is absorbed by the sand or well, the oil or heat carrying fluid will return to the heating device at a diminished temperature, but as the well and strata become warm the oil will return at a continuously higher temperature, so that less heat energy will be required to maintain a predetermined maximum temperature in the well. The rock or sand in the oil bearing strata are very slow conductors of heat, and it is not economical to supply heat faster than it can be absorbed. To control this heat supply a thermostatic regulator is preferably made a part of the heat generating device, which can be adjusted so as to heat the oil to a predetermined maximum temperature and which automatically cuts off the supply of fuel to the burners of the heat generating device, as the oil returning from the well becomes gradually hotter, thus using only such an amount of fuel as necessary to raise the oil from its returning temperature to the predetermined maximum temperature. When the oil approaches the predetermined maximum temperature when returned from the well, because the well and strata have become too hot to absorb more heat, then the thermostatic regulator automatically turns off all the fuel supply to the burners, with the exception of a small pilot flame. The heat in the well will continue to penetrate into the strata for a considerable period of time, but the amount of heat required to maintain the well at the predetermined balanced temperature is very small. Because the oil-bearing strata is overlaid with several hundred feet of insulating material, when heat has been once absorbed into the rock strata it remains there indefinitely or for a considerable period of time, as the leakage or depletion of heat from the well and strata is represented directly by the amount of heat carried in the oil piped off for storage and sale. This amount of heat leakage is extremely small. The specific heat of petroleum oil is less than 0.5 of a British thermal unit per degree Fahrenheit for one pound of oil, and the heat lost may be taken as the difference between the ground temperature, say 65°, and the outgoing oil temperature of 125° or 60°. Calling the weight of a barrel of oil 300 pounds

this represents 9,000 heat units or the equivalent of only nine feet of the lowest quality of natural gas. This illustration is given to show the low cost of maintaining the well in a balanced heat condition and of heating the outgoing oil. 70

Another advantage and object of the invention is not only to increase the flow and yield of the well, but to render, as indicated above, thick viscous oils thinner, so that they will flow freely through the delivery pipes to the crude oil storage tanks, and this feature is especially valuable in cold climates. 75

Another valuable product of an oil well is the casing-head or hydrocarbon gas carrying large amounts of volatile vapors which are utilized in compression and absorption plants for the making of gasoline. The amount of casing-head gas is greatly increased by this process as well as its content of gasoline making hydrocarbons. This object and result is claimed as a valuable feature of my invention. Incidentally, the total cost of installation and maintenance of the apparatus and process is paid for by the increased gas production, without regard to the increased amount of casing-head gasoline line produced. 80

In the accompanying drawing to be taken as a part of this specification, I have shown an apparatus which I have invented for efficiently carrying out the said process constituting my invention, in which drawing, said apparatus is shown in side elevation and partly in longitudinal section, some parts being indicated diagrammatically. 90

Referring to the drawings by characters of reference, 1 designates a well casing which may be of any of the well known constructions without departing from my invention. 100

2 designates the earth stratum, or so-called "oil-sand," into which the casing is driven or lowered. 110

The well casing may be provided with the usual casing-head 2^a supporting a pump tubing 3, in which is arranged a pump rod 4 for operating a pump piston 5, all of which may be of any well known or suitable construction. The pump rod 4 projects above the casing and is connected to a suitable lever mechanism 6 by means of which the pump is operated or reciprocated to elevate the oil from the well. The pump tubing 3 is connected by an outlet pipe 7 to a receiving chamber 8 into which the oil is pumped by means of the pump mechanism heretofore described. The receiving chamber 8 opens at its upper portion into an outlet pipe 9 through which the oil flows into a heating coil 10 arranged within the casing of a heater 11 provided with a suitable burner 12. The receptacle or chamber 8 is provided preferably with a central flue 13 leading to a 120

125

130

stack 14, and through which flue the products of combustion pass from the burner 12 in order to initially heat the body of oil contained in said chamber 8. This initially heated body of oil flows from the chamber 8 through the pipe 9 into the heating coil 10, where it is further heated and passes from an outlet pipe 15 to the interior of the well casing 1, the said pipe 15 being projected through the casing-head 2^a into the interior of the casing, as at 16, for the purpose stated. The oil elevated by the pump piston passes through the pipe 7, is heated by the heating element comprising preferably the chamber 8, and coil 10, whereupon said oil in its heated condition is flowed into the casing to impart and maintain the desired temperature in the well and in the oil-bearing stratum.

Connected to the casing-head 2^a is a pipe section 17 which opens into a pipe 18 by means of which casing-head gas may be transmitted to any suitable collector, or means for treating said gas, for example, an apparatus for recovering hydrocarbon constituents from said gas. This pipe 18 may be connected by a branch pipe 19 to the burner 12, said pipe 19 being controlled preferably by a thermostatic valve 20 connected by a conductor 21 to a thermo-couple or other thermostatic device 22 subjected to the temperature of the oil flowing from the coil 10, the arrangement being such that said valve 20 is controlled to regulate the amount of fuel gas fed to the burner 12, in order to maintain the oil passing from the heating device at a constant predetermined maximum temperature irrespective of the amount of oil flowing through the heating device. The upper portion of the heating chamber 8 may be connected by a vapor pipe 23 to the said pipe 18 so that the vapors given off the oil in said chamber may be delivered to the said pipe 18, and a portion burned in the burner 12, or passed with the casing-head gas to suitable storage or treatment. The pipe 7 is connected to a pipe 24 discharging into a collector or storage tank 25. The pipe 7 is provided with a controlling valve 26 between the heater and said pipe 24, and the pipe 24 is provided with a valve 27. By positioning the valves 26 and 27, the entire body of oil may be caused to pass through the heating device and be heated therein, in order to carry heated oil back to the well casing, or a portion of the oil pumped from the well may be diverted through the pipe 24 into the storage tank or collector 25, or the entire body of oil pumped from the well may be delivered to the storage or collector 25.

By means of the thermostatic regulator, the temperature of the oil passing from the heating device to the well may be maintained at a constant predetermined maximum temperature, irrespective of the amount of

oil which flows through the heater. As the process continues, the heat of the oil in the well will be increased, and the thermostatic regulator in response to these increases of heat will regulate the supply of fuel to the burners so as to diminish the supply as the heat requirement is lessened.

The oil heater may be provided with a release valve 28 in order to permit the escape of vapors generated therein through the pipe connection 23 to the casing-head gas delivery pipe 18 from the well casing, in order that the gas collected in the oil chamber 8 may pass to the casing-head delivery pipe, and thereby be conserved.

I preferably provide a drain valve 29 at the bottom of the chamber 8, in order that water and sludge which collects in the bottom of said chamber may be drawn off. By having the inlet pipe from the oil well pump discharging into the chamber 8 at an opening above the bottom thereof, and arranging the outlet to the pipe 9 above said inlet from the pipe 7 and toward the top of the heater 8, the said heater will serve as a separator of water and sediment carried by the oil from the well, which water and sediment may be drawn off through the said drain 29, heretofore described.

In operation, the process embodying my invention is performed by the above described apparatus as follows: The oil pumped from the well is elevated through the pump tubing 3 and delivered through the pipe 7 to the chamber 8 where it is preferably initially heated, and water and sludge separated therefrom, said oil passing from said chamber into the pipe 9, whence it flows into the heating coil 10, and is further heated and flows from said coil into the pipe 15, whence it is delivered into the well casing from the outlet pipe 16. By this operation, the oil elevated from the well is heated, and operating as a heat carrier flows back into the well, thereby serving to transmit the heat to the hydrocarbon oils in the well and the oil-bearing strata, for purposes hereinbefore set forth.

In the preferred embodiment of the process, I preferably employ the hydrocarbon fluid contents of the well being treated as the heat transmitting medium, but I desire it understood that I do not limit myself to the use of the hydrocarbons originating in the well being treated, but may, under certain circumstances, employ fluid hydrocarbon from another source in order to initiate a proper circulation and transmission of heat to the oil in the well, and the oil bearing strata. This may be advisable in cases where the hydrocarbon contents of the well are not sufficient in amount to serve efficiently as the heat carrier. It may also be advisable where the hydrocarbon contents of the well have solidified to the extent that

- they cannot be satisfactorily pumped until their fluidity has been increased. In the latter cases, the oil to be used may be taken from any suitable source, for example, the 5 container 8 designed to contain sufficient oil for the purpose, or the oil may be taken from another well, and pumped to the well casing from which it may be circulated in the manner heretofore described.
10. What I claim and desire to secure by Letters Patent of the United States is:—
1. The method of increasing the production of an oil well consisting in maintaining the oil bearing stratum adjacent the well at a 15 temperature above normal and sufficiently high to reduce the viscosity of the oil therein and facilitate its flow toward the well by discharging heated liquid into the well in a sufficiently continuous supply to maintain 20 the desired temperature in said stratum and removing the same in the usual pumping operation.
  2. The method of increasing the production of an oil well consisting in maintaining 25 the oil bearing stratum adjacent the well at a temperature above normal and sufficiently high to reduce the viscosity of the oil therein and facilitate its flow toward the well by heating crude oil, discharging such heated 30 oil into the well in a sufficiently continuous supply to maintain the said stratum at the desired temperature and removing said oil together with the new oil produced in the well in the usual pumping operation.
  3. The method of increasing the production of an oil well consisting in maintaining the oil bearing stratum adjacent the well at a temperature above normal and sufficiently 35 high to reduce the viscosity of the oil therein and facilitate its flow toward the well by heating more or less of the crude oil obtained from the well, delivering the heated oil into the well in a sufficiently continuous 40 supply to maintain said stratum at the desired temperature and removing the oil in 45 the usual pumping operation.
  4. The method of increasing the production of an oil well consisting in maintaining the oil bearing stratum adjacent the well at a temperature above normal and sufficiently 50 high to reduce the viscosity of the oil therein and facilitate its flow toward the well by heating more or less of the crude oil obtained from the well to a predetermined temperature, delivering the heated oil into 55 the well in a sufficiently continuous supply to maintain said stratum at the desired temperature and removing the oil in the usual pumping operation.
  5. In an apparatus for increasing the production of an oil well, the combination with the well and the oil pump therein of an oil heater outside the well, means for conveying oil from the pump to the oil heater, and means for conveying oil from the heater and 60 delivering it into the well, for the purpose set forth.
  6. In an apparatus for increasing the production of an oil well, the combination with the well and the oil pump therein of an oil 65 heater outside the well, means for conveying oil from the pump to the oil heater, means for regulating said heater whereby the temperature of the oil discharged therefrom will be substantially uniform, and 70 means for conveying oil from the heater and delivering it into the well, for the purpose set forth.
- In testimony whereof I have hereunto signed my name in the presence of the sub- 80 scribing witnesses.

WILLIAM JOHN KNOX.
